United States Patent Office

Des. 216,322
Patented Dec. 16, 1969

216,322

COMBINED PENDANT WATCH AND RADIO

Frank J. Forey, 3057 Leeward Ave.,
Los Angeles, Calif. 90005

Filed Dec. 16, 1968, Ser. No. 14,971

Term of patent 14 years

Int. Cl. D10—02

U.S. Cl. D42—8

FIG. 1.

FIG. 2.

FIG. 3.

FIG. 4.

FIG. 5.

FIG. 6.

FIGURE 1 is a top plan view of a pendant watch and radio showing my new design;

FIGURE 2 is a back plan view thereof;

FIGURE 3 is a front elevational view;

FIGURE 4 is a rear elevational view;

FIGURE 5 is a right side elevational view; and

FIGURE 6 is a left side elevational view.

I claim:

The ornamental design for a combined pendant watch and radio, substantially as shown.
